UNITED STATES PATENT OFFICE

ANTHONY VAN GYTENBEEK, OF PATERSON, NEW JERSEY

DESIGN FOR A TOY SAVINGS BANK

Application filed May 29, 1930. Serial No. 35,849. Term of patent 3½ years.

To all whom it may concern:

Be it known that I, ANTHONY VAN GYTENBEEK, a citizen of the United States, residing at the city of Paterson, county of Passaic, and State of New Jersey, have invented a new, original, and ornamental Design for Toy Savings Banks, of which the following is a specification.

The figure is an isometric view of a toy savings bank showing my new design. The device presents substantially the same appearance when viewed from either side.

I claim:

The ornamental design for a toy savings bank, as shown and described.

In testimony whereof I affix my signature.

ANTHONY VAN GYTENBEEK.
